Specification for Design.

Patented Mar. 25, 1919.

Application filed August 30, 1916. Serial No. 117,808. Term of patent 3½ years.

To all whom it may concern:

Be it known that I, JOHN S. MONAGHAN, a citizen of the United States, and a resident of the city of Rochester, county of Monroe, and State of New York, have invented a new, original, and ornamental Design for Buttons, of which the following is a specification.

My design is represented in the accompanying drawing, in which:

Figure 1 is a plan view of a button showing my new design.

Fig. 2 is a side elevation.

Fig. 3 is a section on the central line.

The button is circular in shape, the side of which is cylindrical, the bottom of which

is substantially flat, the upper surface of which is conical and is provided in the center with a cavity, the surface of which is concave.

I claim:

The ornamental design for a button substantially as shown and described.

In witness whereof I have hereunto set my hand at Rochester, in the county of Monroe and State of New York, this 25th day of August, 1916.

JOHN S. MONAGHAN.

In presence of—

EARL A. WELLER,
